UNITED STATES PATENT OFFICE

FRED C. MYER, OF SACRAMENTO, CALIFORNIA

VENDING MACHINE

Application filed September 9, 1929. Serial No. 391,391.

This invention relates to improvements in package vending machines, and more particularly to the mechanism for releasing one package at a time from a stack of packages in a container.

The principal object of the invention is to provide a simple means for releasing a package from the bottom of the pile and of dropping the pile down on to holding means so that the bottom package is ready for the next delivery.

Another object is to provide means to operate the releasing mechanism by means of an inserted coin.

Another object is to provide a set of opposed dogs for holding the stack of packages up while the bottom package is being released or it drops out, and another set of opposed dogs for releasing the bottom package.

Other objects of the invention will be apparent as the description proceeds.

In this specification and the accompanying drawings the invention is disclosed in its preferred form. But it is to be understood that it is not limited to this form because it may be embodied in other forms. It is also to be understood that in and by the claims following the description it is desired to cover the invention in whatsoever form it may be embodied.

Figure 1 is a sectional side view of the vending machine taken on line 1—1 of Figure 2.

Figure 2 is a front sectional view taken on line 2—2 of Figure 1.

Figure 3 is a modified form of releasing mechanism partly broken away for purposes of illustration.

The numeral 1 indicates the casing or housing for packages and operating mechanism. The guides 2, 3, 4 and 5 are fixed to the casing to keep the packages 6 in alignment in stack form. The rod 9 is mounted in the guides 2—3 and carries the depending dogs 7 and 8.

The rod 12 is fixed to the guides 4—5 opposite the rod 9 and carries the dogs 10—11.

The dogs have the hook like package support members 13.

Mounted below these dogs on the rod 14 is a pair of dogs 15 and 16, and on the rod 17 is a pair of dogs 18 and 19. The rods 14 and 17 being supported in the guides 2 to 5 inclusive. The dogs 15, 16, 18 and 19 have hook like package supporting members 20.

Pivoted on the bolt 21 in the casing is the lever 22, the movement of which is limited by the slot 23 in the front of the casing. A spring 24 acts to hold the lever in the raised position.

Links 25 and 26 pivoted at their outer ends to the dogs 7 and 10 at 27 and 28, and to the link 29 at 30. The link 29 is pivoted to the inner ends of the links 25 and 26 and to the lever 22 at 31. On the same pivot is the pendant link 32, and it has the pivot 33 at its lower end to which the links 34 and 35 are attached. The outer ends of these links are pivoted at 36 and 37 to the dogs 16 and 18.

When the lever 22 is in the raised position the links act to pull the upper dogs in, and push the lower dogs out as shown in Figure 1. The upper dogs hold up the stack of packages and the lower dogs release the bottom package where it falls near the opening 38 in the casing where it can be picked up.

The above described vending mechanism would operate to release one package at a time free, but provision is made for coin release of the lever by means of the coin chute 39.

The lever is locked in the up position by the latch 40 pivoted at 41, and it has the short arm 42 in the path of downward motion of the arm 43, which arm receives the coin and a projection 44 on the lever presses down on the coin and carries the arm 43 down which releases the latch 40 and allows the lever to move down and operate the package releasing device.

In the modified form shown in Figure 3 45 indicates the casing, and 46 and 47 the package guides. 48 is the hand lever which is held in the raised position by the spring 49 and pivoted on the casing at 50.

5 A link 51 is pivoted on the lever at 52, and this lever has the links 53 and 54 pivoted on its upper end at 55. These links are pivoted at their outer ends at 56 and 57 to dogs 10 58 and 59 pivoted on the rods 60, 61 in the brackets 62. On the casing spaced from the dogs on the rods, are the duplicate dogs 63 and 64.

Each dog has the inturned catch 65 on the 15 lower end, and the pivoted friction stop 66 at the upper end. This form may have the same means for locking the lever and the release thereof by a coin, but it is not shown in this instance as the modification relates to the 20 package release means only.

The operation of the coin release and package delivery shown in Figures 1 and 2 is as follows:

The coin is inserted in the coin slot and 25 drops down the chute 39 and rolls out at the bottom onto the lever 22, which is now pressed down carrying the coin and arm down with the lever on the pivot 21, the arm coming in contact with the projection 42 on the latch 30 40 throws the latch out of the path of motion of the lever and allows it to continue moving, and through the link 29 pulls the links 25 and 26 down to a straight position thereby pushing out the dogs connected thereto and 35 releasing the pile of packages, at the same time through the link 32 the links 34 and 35 are pushed down pulling in the dogs connected with these links and catching the descending packages.

40 When the lever is released the spring pulls it up which action throws the lower dogs out and releases the package, and throws the upper dogs to hold the stack of packages.

While in the above description, packages 45 are stated as the article vended, it will be seen that the device could be made large enough for any size package, and small enough for any single article.

Having thus described my invention, what 50 I desire to secure by Letters Patent of the United States is as follows, but modifications may be made in carrying out the invention, and in the annexed drawings, as defined by the claims:

55 1. A vending machine comprising a casing having a magazine to receive a stack of packages, a plurality of opposed dogs pivoted in said casing and adapted to engage the lowermost package, a toggle joint connecting said dogs, a second set of dogs pivoted in said casing and adapted to engage the adjacent package, a second toggle joint connecting said dogs, and means to operate said toggle joints synchronously.

60 65 2. A vending machine comprising a cas-

ing having a magazine to receive a stack of packages, a plurality of opposed dogs pivoted in said casing and adapted to engage the lowermost package, a toggle joint connecting said dogs, a second set of dogs pivoted in said casing and adapted to engage the adjacent package, a second toggle joint connecting said dogs and holding said dogs in a reverse position in respect to the first dogs, a link joining said toggle joints, and 70 operating means for said link.

In testimony whereof I have hereunto set my hand this 5th day of August A. D. 1929.

FRED C. MYER.
